192,693

EGG BOILER UTENSIL

Nadina Billi, 155 E. 34th St., New York, N.Y.

Filed July 17, 1961, Ser. No. 65,939

Term of patent 14 years

(Cl. D44—1)

Fig. 1.

Fig. 2.

Des 192,693

PAGE 2

FIG. 5.

FIG. 1 is a front elevational view of an egg boiler utensil, showing my new design;

FIG. 2 is a top plan view thereof;

FIG. 3 is a bottom plan view thereof;

FIG. 4 is a sectional view taken with the cover in open position; and

FIG. 5 is a perspective view thereof in open condition.

I claim:

The ornamental design for an egg boiler utensil, substantially as shown and described.
